REFINING OF MINERAL OILS

William O. Heilman, Cranford, N. J., assignor to
Standard Oil Development Company, a corpora-
tion of Delaware

Application February 24, 1941, Serial No. 380,273

6 Claims. (Cl. 196—32)

The present invention is concerned with the refining of mineral oils. The invention is more particularly concerned with an improved operation comprising a particular arrangement and sequence of stages for the removal of mercaptan compounds from petroleum oil, especially when using an alkali metal hydroxide solution. In accordance with the present process, the feed oil is segregated into a relatively low boiling fraction and into a relatively high boiling fraction. The segregated fractions are contacted with alkali metal hydroxide solutions withdrawn from a common storage. The spent alkali metal hydroxide solutions are segregated from the respective treating zones, regenerated and returned to the storage zone. The spent alkali metal hydroxide solution withdrawn from the treating zone utilized in the removal of mercaptan compounds from the relatively low boiling petroleum oil fraction is treated with an oxygen containing gas in a manner to convert the mercaptides to the corresponding disulfides. The alkali metal hydroxide solution containing the disulfides is combined with the caustic solution withdrawn from the treating zone wherein the relatively high boiling petroleum oil fraction is treated, and the mixture steam distilled under conditions to convert the relatively high boiling mercaptides to the corresponding mercaptans which are removed overhead along with the disulfide constituents. The regenerated alkali metal hydroxide solution is withdrawn as a bottoms product and recycled to the respective treating zones.

It is known in the art to refine petroleum oils by various procedures, particularly for the removal of mercaptan compounds therefrom. One method employed, for example, is to treat the feed oil with a so-called "doctor solution," which usually comprises a saturated solution of lead oxide dissolved in a sodium hydroxide solution. When a feed oil containing mercaptans is treated with this solution the mercaptans are converted to lead mercaptides which are soluble in the oil being treated. The oil solution containing the soluble lead mercaptides is contacted with a reagent adapted to precipitate the lead compounds and to convert the sulfur compounds to disulfides. This is usually accomplished by the addition of free sulfur, resulting in the formation of lead sulfide and the corresponding alkyl disulfides. This operation is not entirely satisfactory, particularly in the treatment of relatively high boiling oils, for several reasons. One disadvantage is that it is relatively difficult to control the exact amount of sulfur necessary to secure the complete

precipitation of the lead as lead sulfide. If too little sulfur is added, some of the lead remains dissolved in the oil as soluble lead mercaptides which results in the production of an oil of inferior quality, particularly with respect to its stability and burning properties. If an excess of sulfur be added, the excess sulfur dissolves in the oil and materially increases its corrosiveness and substantially affects its other desirable properties. It has, therefore, been suggested that other operations be employed which will not only remove the mercaptans but will also function to secure an overall reduction in the sulfur content of the final product. One process suggested is to treat the oil with an alkali solution, as for example, a sodium hydroxide solution. Operations of this character have not heretofore been entirely satisfactory for the reason that the relatively high boiling mercaptans present in the oils boiling in the heavy naphtha and heating oil boiling ranges are not particularly reactive therewith resulting in only a partial removal of the mercaptans unless an excessive and prohibitive quantity of the reagent be employed.

I have, however, now discovered an operation by which it is possible to efficiently and economically remove relatively high boiling mercaptans present in these relatively high boiling oils utilizing a relatively low quantity of the alkali metal hydroxide solution based upon the total volume of oil being treated. My process comprises segregating the feed oil into a relatively low boiling fraction and into a relatively high boiling fraction. I treat the relatively low boiling fraction and the relatively high boiling fraction in separate contacting zones with an alkali metal hydroxide solution withdrawn from a common source or which is directly recycled from the regeneration zone and which preferably comprises revivified and regenerated alkali metal hydroxide solution produced in a manner as hereinafter described. The operating conditions in the respective zones are adjusted to secure complete removal of the mercaptan compounds from the feed oils. The spent alkali metal hydroxide solution withdrawn from the zone wherein the relatively low boiling fraction is treated is withdrawn and subjected in a tertiary zone to contact with an oxygen-containing gas under conditions to convert the mercaptides to corresponding disulfide compounds. This spent hydroxide solution is withdrawn from said tertiary zone and combined with the spent hydroxide solution withdrawn from the zone wherein the relatively high

boiling petroleum oil fraction is treated. The

mixture is passed to a regeneration zone in which the same is treated to remove the mercaptans and disulfides from the spent alkali metal hydroxide solution. This is preferably secured by steaming the combined alkali metal hydroxide solution streams under conditions to convert the mercaptides to the corresponding mercaptans which are removed overhead from the regeneration zone along with the disulfide compounds produced in the tertiary zone. The regenerated alkali metal hydroxide solution substantially completely free of sulfur compounds is removed and recycled to the respective treating zones.

My process may be readily understood by reference to the attached drawing illustrating an embodiment of the same. For the purpose of description it is assumed that the feed oil comprises a petroleum oil boiling in the motor fuel boiling range. The feed oil is introduced into distillation zone 1 by means of line 2 in which it is segregated into a relatively low boiling fraction which is removed by means of line 3, and into a relatively high boiling fraction which is removed by means of line 4. The relatively low boiling fraction is introduced into primary treating zone 5 wherein it is contacted with an alkali metal hydroxide solution which for the purpose of description is taken to be a sodium hydroxide solution and which is introduced into zone 5 by means of line 8. Temperature and pressure conditions and other operating conditions are adjusted to secure substantially complete removal of the mercaptan compounds from the low boiling fractions. The treated fraction is removed from treating zone 5 by means of line 6 and handled or further refined in any manner desirable. The relatively high boiling fraction is introduced into secondary treating zone 7 in which it is treated with a sodium hydroxide solution which is introduced into zone 7 by means of line 22. Temperature and pressure conditions are similarly adjusted as well as other operation conditions in order to secure complete removal of the mercaptan compounds from this fraction. The treated high boiling fraction is removed from zone 7 by means of line 9, combined with the treated relatively low boiling fraction and withdrawn as a mercaptan free product from the system by means of line 10. The spent sodium hydroxide solutions are withdrawn from zones 5 and 7 by means of lines 11 and 12 respectively. The spent sodium hydroxide solution withdrawn from primary treating zone 5 is introduced into tertiary zone 13 wherein it is contacted with an oxygen containing gas which is introduced by means of line 14. Conditions are adjusted in zone 13 to convert the relatively low boiling mercaptan compounds to the corresponding disulfides and to remove overhead by means of line 15 the treating gas. The hydroxide solution containing the disulfide compounds is withdrawn from tertiary zone 13 by means of line 16 and combined with the spent hydroxide solution withdrawn from zone 7 by means of line 12. The mixture is introduced into regeneration zone 17 and the sulfur compounds removed overhead as mercaptans and disulfides from the sodium hydroxide solution. This is preferably accomplished by introducing steam by means of line 18 and maintaining conditions in zone 17 adapted to convert the mercaptides in the stream withdrawn from zone 7 to the corresponding mercaptans and to remove the same overhead by means of line 19 along with the disulfide compounds. A regenerated caustic solution sub-

stantially completely free of sulfur compounds is withdrawn from zone 17 by means of line 20, passed to storage 21 and recycled to the respective primary and secondary treating zones by means of line 22 and line 8.

The process of the present invention may be widely varied. It is to be understood that zones 1, 5, 7, 13 and 17 may comprise any suitable number and arrangement of units. Under certain conditions, it may be desired to reconcentrate the caustic solution returned to storage 21. If this operation be employed, the caustic solution is passed to reconcentration unit 23 by means of line 24. Temperature and pressure conditions are adapted to remove overhead by means of line 25 water and to remove by means of line 26 a reconcentrated solution.

By operating in the manner described it is possible to remove more efficiently and economically mercaptan compounds from feed petroleum oils which boil over a relatively wide range. Although a potassium hydroxide solution may be employed, it is preferred to employ a sodium hydroxide solution, particularly one having a concentration in the range from 15% to 30% sodium hydroxide. The amount of alkali metal hydroxide solution utilized per volume of oil will be sufficient to secure the desired removal of the mercaptan compounds. In general, the amount necessary is in the range from about 15% to 30% based upon the total volume of feed oil being treated. The amount necessary will depend upon the character of the mercaptan compounds present, their concentration, and the boiling range of the feed oil being treated.

Although the feed oil may be segregated into a relatively low boiling fraction and into a relatively high boiling fraction of approximately equal volume, wherein the final boiling point of the low boiling fraction and the initial boiling point of the high boiling fraction approximate the mid-boiling point of the feed oil, and the respective streams contacted in the primary and secondary treating zones with an alkali metal hydroxide solution which has been approximately equally segregated, I have found that particularly desirable results are secured providing the feed oil be segregated into a relatively low boiling fraction which comprises about 60% to 80% of the total feed oil and into a high boiling fraction which is about 20% to 40% of the feed oil. The feed oil fraction segregated in this manner may be contacted in the respective treating zones with alkali metal hydroxide streams which have been segregated in about equivalent volumes. However, it is preferred to segregate the alkali metal hydroxide stream, which is withdrawn from the storage zone or which is being recycled from the regeneration zone, into a stream comprising about 20% to 40% of the total alkali metal hydroxide solution employed, which stream contacts the relatively large volume of the low boiling feed oil fraction, and into a relatively large alkali metal hydroxide stream which comprises from about 60% to 80% of the total alkali metal hydroxide stream, and to utilize the same in contacting the relatively small quantity of the feed oils comprising the relatively high boiling fraction in the secondary treating zone. When operating as described, mercaptan compounds are efficiently and economically removed from a feed oil containing the same, whereby it is possible to use an unexpectedly low amount of the reagent, thus materially effecting operating economies. It is also possible to regenerate the

treating reagent efficiently by utilizing a minimum amount of steam. Furthermore, the relatively low boiling mercaptans which are difficultly hydrolyzable are converted to higher boiling disulfides which boil approximately in the range of the relatively higher boiling mercaptans, which are regenerated from the mercaptides present in the alkali metal hydroxide utilized in the treatment of the relatively higher boiling petroleum oil fraction under these conditions.

What I claim as new and wish to protect by Letters Patent is:

1. Process for the removal of mercaptan compounds from a feed oil boiling in the motor fuel boiling range, which comprises segregating the feed oil into a relatively low boiling fraction and into a relatively high boiling fraction, contacting the relatively low boiling fraction in a primary treating zone with an alkali metal hydroxide solution under conditions to remove mercaptan compounds, separating the relatively low boiling fraction from the alkali metal hydroxide solution, withdrawing said alkali metal hydroxide solution from the primary treating zone and treating the same in a tertiary zone with an oxygen containing gas under conditions to convert mercaptide compounds present therein to the corresponding disulfides, treating the relatively high boiling fraction of the feed oil in a secondary treating zone with an additional quantity of alkali metal hydroxide solution under conditions to remove therefrom mercaptan compounds, separating said treated relatively high boiling fraction and combining the same with said treated relatively low boiling fraction to produce a finished product, separating the alkali metal hydroxide solution from said secondary treating zone and combining the same with the alkali metal hydroxide solution withdrawn from said tertiary zone, treating the combined streams with steam under conditions to remove the sulfur compounds therefrom, and recycling the regenerated alkali metal hydroxide solution to said primary and said secondary treating zones.

2. Process as defined by claim 1, in which said

alkali metal hydroxide solution comprises a sodium hydroxide solution.

3. Process as defined by claim 1, in which said feed oil is segregated into a relatively low boiling fraction which comprises from about 60% to about 80% of the feed oil and into a relatively high boiling fraction which comprises from about 20% to about 40% of the feed oil.

4. Process as defined by claim 1, in which said feed oil is segregated into a relatively low boiling fraction which comprises from about 60% to about 80% of the feed oil and into a relatively high boiling fraction which comprises from about 20% to about 40% of the feed oil, and in which the segregated feed oil fractions are treated in the respective treating zones with an equal amount of recycled alkali metal hydroxide solution.

5. Process as defined by claim 1, in which said feed oil is segregated into a relatively low boiling fraction which comprises from about 60% to about 80% of the feed oil and into a relatively high boiling fraction which comprises from about 20% to about 40% of the feed oil, and in which the relatively low boiling fraction of the feed oil is contacted in said primary treating zone with from about 20% to about 40% of the alkali metal hydroxide solution based upon the total quantity of solution used, and in which said relatively high boiling fraction is treated with about 60% to 80% of the alkali metal hydroxide solution based upon the total quantity of solution used.

6. Process as defined by claim 1, in which the alkali metal hydroxide solution comprises a sodium hydroxide solution and in which said solution is regenerated prior to recycling the same to the respective treating zones utilizing steam under conditions to convert the mercaptides present in the alkali metal hydroxide solution withdrawn from said secondary treating zone to the corresponding mercaptans and under conditions in which said mercaptans along with the disulfides produced in said tertiary zone are removed overhead.
